CLAIM

The ornamental design for an elephant toy, as shown and described.

DESCRIPTION

FIG. 1 is a perspective view of an elephant toy showing our new design;

FIG. 2 is another perspective view thereof;

FIG. 3 is a front elevational view thereof;

FIG. 4 is a rear elevational view thereof;

FIG. 5 is a left side view thereof;

FIG. 6 is a right sideview thereof;

FIG. 7 is a top plan view thereof;

FIG. 8 is a rear elevational view thereof; and,

FIG. 9 is a partial enlarged view taken from FIG. 1 thereof. The broken lines depict portions of the elephant toy that form no part of the claimed design.

The dot-dash broken lines indicating an enlargement portion of the design form no part of the claimed design.

1 Claim, 9 Drawing Sheets
